UNITED STATES PATENT OFFICE.

JOSEPH E. ALM, OF SAN FRANCISCO, CALIFORNIA.

EXPANSIBLE BELT CONNECTER.

Application filed December 22, 1926. Serial No. 156,272.

This invention relates to a belt connector, such as used for wearing apparel, trouser belts and the like and especially to a connector which is resilient or yielding in construction.

The great majority of wearing apparel belts such as trouser belts and the like are usually constructed of non-resilient materials such as leather, cloth, fabrics and the like. The main objection to belts of this character is lack of resilient yielding action or free body moving when stooping, bending, etc., and trouser belts are for this reason often discarded in favor of ordinary elastic suspenders.

This particular invention embodies a belt connector which is resilient or expansible in operation. The general feature being to generally improve and simplify the construction and operation of devices of this character and, particularly, to provide a belt connector which is not only artistic in appearance and substantial in construction, but sufficiently resistable to permit the use of non-elastic parts without resisting or interfering with free body movement. The invention is shown by way of illustration in the accompanying drawings, in which:

Figure 1 is a plan view of the belt connector, said view being partly broken away and being shown partly in section,

Figure 2 is a side elevation which is shown as partly broken away and partly in section,

Figure 3 is a cross section taken on the line III—III of Figure 1,

Figures 4 and 5 are perspective views of the link members forming the expansible belt connector.

Figure 6 is a plan view of the blank forming one of the link members,

Figure 7 is a perspective view showing the application of the invention to an ordinary belt.

Referring to the drawings, in detail, and particularly Figures 1, 4, 5 and 6, it will be noted that the expansible belt connector consists of two link members, generally indicated at A and B. These link members are substantially identical in construction and the description of one should, accordingly, suffice. The link members are cut by dies or the like in a punch press of comparatively thin sheet metal, such as brass, German silver or the like and the blank form is that indicated in Figure 6.

The link consists of a head member 2 and a cross bar 3. The head and the cross bar is connected by strips or link arms 4 and the cross bar is provided with a second series of link arms or strips as indicated at 5. The last-named link arms are bent with relation to the cross bar as shown in Figures 4 and 5 and front and rear link arms are thus formed. The head member 2 is curled or bent upon itself as indicated at 6 (see Figure 4) to retain and embrace an elongated wire loop 7. The coiled end of the head member is recessed in alignment with the arms 5 as shown at 8 and the forward ends of the arms are offset as at 8^a to form retaining lips 9 which are inserted through the notch portions 8 to permit the lips 9 to interlock with the head member as indicated at 10 (see Figure 2). The link thus blanked and bent consists of a plurality of front and rear link arms which forms the link shown in Figure 4. The second link indicated in Figure 5, as already stated, is substantially identical in construction, the only difference being that the arms indicated at 4^a form the front arms and the arms indicated at 5^a the rear arms. Another difference will be noted to this extent that the outside arms 5^a are provided with side flanges 11 which serve the function of retaining a spring, generally indicated at C (see Figure 1).

The two link members are assembled in the condition shown in Figures 4 and 5. The front arms 4^a of the link A will thus pass between the front arms 4 of the link B and the rear arms 5 of the link B will pass between the rear arms 5^a of the link A. The arms 5 and 5^a will lie in a common plane and so will the link arms 4 and 4^a. When the links are thus assembled the spring C is placed between the arms and the free ends 9 and 9^a of the respective links are passed in under the notches 8 of the respective head members and a complete interlock is thus formed. The front and rear arms of the respective links are interspaced with relation to each other sufficient distance to receive the springs C and the flanges 11 being bent upwardly as shown in Figures 2, 3 and 5 to retain the spring against removal. With the spring thus located and the links completely assembled, it will be noted that the crossbar 3 of the link B will lie adjacent the head member 2^a of the link A and that

the cross bar 3^a of the link A will lie adjacent the head member 2. Similarly, that the cross bar 3 will lie between the arms 4^a and 5^a of the link A and that the cross bar 5 3^a will lie between the arms 4 and 5 of the link B. If a pull is exerted on the loops 7 and 7^a, the links will separate longitudinally and the cross bars 3 and 3^a will advance towards each other. This places the 10 spring C under compression and when the pull on the loops 7 and 7^a is released the movement will be in a reverse direction and the links will assume the normal position shown in Figure 1. As previously stated, 15 the link arms 4^a of link A lie between the link arms 4 of the link B and on a common plane and so do the link arms 5 and 5^a, this being permitted as the recesses 12 are formed in the respective cross bars. These 20 recesses are of a depth equal to the thickness of the respective link arms.

The expandible belt connecters are preferably employed as shown in Figure 7, that is, an ordinary leather or fabric belt is made 25 in three sections, a back section 14 and two front sections 15 and 16. The belt connecters are interposed between the front and rear sections of the belt, as indicated at 17 and 18 and the front sections are otherwise 30 provided with an ordinary belt buckle as indicated at 19 to permit the belt to be adjusted about the waist as desired. By interposing the belt connecters as shown at 17 and 18, complete freedom of body movement 35 is obtained as the links form the respective belt connecters and will yield with relation to each other, as movement takes place.

Any suitable type of spring may be interposed between the link sections, but a practical form of spring is illustrated in Figure 40 1. It consists of a single piece of ordinary spring steel wire, bent to form the spring loops indicated at 20, 21 and 22. These loops are connected by the arms 23 and terminate in end sections 24 which engage the inner surfaces of the cross bars 3 and 3^a. A 45 spring of this character exerts a fairly uniform tension and uniform resistance or pull is exerted as the link sections are extended 50 or retracted with relation to each other.

While certain features of the present in-

vention are more or less specifically described, I wish it understood that various changes may be resorted to within the scope of the appended claims. Similarly that the materials and finishes of the several parts employed may be such as the manufacturer may decide or varying conditions or uses 55 may demand.

Having thus described my invention, what 60 I claim and desire to secure by Letters Patent is:—

1. A device of the character described, comprising first and second-named link members slidable with relation to each other in a longitudinal direction, the first-named link member consisting of a head member and a cross bar connected by a plurality of interspaced front and rear link arms, the second-named link member also consisting of a head member and a cross bar connected by a plurality of interspaced front 65 and rear link arms, the cross bar of the first-named link lying between the link arms of the second-named link and the cross bar of the second-named link lying between the link arms of the first-named link, and a 70 spring member disposed between the link arms of the respective links and engaging the cross bars. 75

2. A device of the character described, comprising first and second-named link members slidable with relation to each other in a longitudinal direction, the first-named link member consisting of a head member and a cross bar connected by a plurality of interspaced front and rear link arms, the second-named link member also consisting of a head member and a cross bar connected by a plurality of interspaced front and rear link arms, the cross bar of the first-named link lying between the link arms of the second-named link and the cross bar of the second-named link lying between the link arms of the first-named link, a spring member disposed between the link arms of the respective links and engaging the cross bars, a loop connected with each head member, and side flanges on one of the links retaining the spring against removal. 90 95
